Primary Examiner — Elizabeth J Oswecki(74) *Attorney, Agent, or Firm* — Che-Yang Chen; Law Office of Michael Chen(57) **CLAIM**

The ornamental design for a shoe insole, as shown and described.

DESCRIPTION

FIG. 1 is a perspective view of a shoe insole showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is an exploded perspective view thereof, showing three pieces of the shoe insole separately for ease of illustration;

FIG. 9 is an exploded front elevational view thereof;

FIG. 10 is an exploded rear elevational view thereof;

FIG. 11 is an exploded right side elevational view thereof;

FIG. 12 is an exploded left side elevational view thereof;

FIG. 13 is an exploded top plan view thereof; and,

FIG. 14 is an exploded bottom plan view thereof.
